(57) **CLAIM**

The ornamental design for a phantom for medical equipment as shown and described.

DESCRIPTION

FIG. 1 is a front, top and right side perspective view of a phantom for medical equipment according to the design; FIG. 2 is an enlarged view of the portion shown in box, labeled, "FIG. 2," in FIG. 1;

FIG. 3 is a front, top and left side perspective view thereof; FIG. 4 is a front, bottom and right side perspective view thereof;

FIG. 5 is a top plan view thereof;

FIG. 6 is a front view thereof;

FIG. 7 is a right side view thereof;

FIG. 8 is a left side view thereof;

FIG. 9 is a rear view thereof; and,

FIG. 10 is a bottom plan view thereof.

The broken lines illustrate portions of the phantom for medical equipment that form no part of the claimed design. The long and short dash broken line box shown in FIG. 1 defines the enlarged portion view shown in FIG. 2 and forms no part of the claimed design.

1 Claim, 10 Drawing Sheets
